UNITED STATES PATENT OFFICE.

ALEXANDER THOMSON, OF SOURLAKE, AND JOHN H. HILL, OF HOUSTON, TEXAS, AS
SIGNORS OF TWO-FIFTHS TO SAID HILL AND THREE-FIFTHS TO R. E. BROOKS, JR.
OF HOUSTON, TEXAS.

PITMAN.

Application filed August 3, 1922. Serial No. 579,431.

This invention relates to new and useful improvements in a pitman.

One object of the invention is to provide a pitman of the character described specially designed for use in operating oil pumps used in pumping the fluid from an oil well.

Another object of the invention is to provide a pitman of the character described having a specially designed bearing to receive the wrist pin of the crank arm through which the walking beam, which operates the pump, is oscillated.

A further feature of the invention resides in the provision of a pitman which is much more durable than the ordinary pitman now in common use, and which may be more easily connected up for operation and disconnected than the present type of pitman.

In pumping an oil well a walking beam is employed which is connected to the power through the pitman, and the pitman must be often connected to and disconnected from the crank arm through which the power is applied. The pitman herein described has been specially designed so that it may be readily connected and disconnected.

A further feature of the invention resides in the provision of a pitman of the character described which may be readily taken up or adjusted so as to take up the wear of the bearing and form a close fit on the wrist pin of the crank arm.

A still further feature of the invention resides in the provision of suitable means for lubricating the bearing.

With the above and other objects in view the invention has particular relation to certain novel features of construction, operation and arrangement of parts, an example of which is given in this specification and illustrated in the accompanying drawings, wherein:—

Figure 1 is a side view of a pitman connection constructed in accordance with this invention.

Figure 2 is a fragmentary longitudinal sectional view of the pitman as installed in connection with the crank arm.

Figure 3 is an edge view of one of the pitman members.

Figure 4 is a plan view thereof.

Figure 5 is an end view.

Figure 6 is a plan view of the other pitman member.

Figure 7 is an end view thereof, and,

Figure 8 is an edge view.

In the drawings the numeral 1 designates the derrick, and the numeral 2 designates a standard which is erected on the derrick floor and upon the upper end of which the walking beam 3 is mounted to oscillate. One end of this walking beam is connected to the pump rod 4 and operates to reciprocate said rod in pumping the well. This end of the walking beam however may be connected to the cable and used in cable tool drilling. The pitman is connected to the other end of the walking beam. The numeral 5 designates the power wheel, which is fixed to the shaft 6 and which is driven in any conventional manner. To one end of the shaft 6 there is fixed a crank arm 7 whose outer end is formed with a wrist pin 8.

The pitman includes a bar 9, preferably formed of metal and which may be connected to the walking beam through a suitable arm 10 formed of wood or metal, and bolted to the bar 9, as shown in Figure 2, and pivoted in any conventional manner to said walking beam. The bar 9 is channel shaped, as shown, and at its free end is formed with a transverse side slot 11, forming a transverse shoulder whose inner end is formed with a half-bearing member 12 which is preferably lined with babbitt or other soft metal 13, and opposite the slot 11 the bar 9 is formed with the hand grip 14. The numeral 15 designates a removable plate having the half-bearing 16, projecting from its inner face and preferably lined with babbitt or other soft metal 17.

The bearing member is shown assembled with the bar 9 in dotted lines in Figure 4 and when so assembled will form a complete bearing in which the wrist pin 8 works. The bar 9 and bearing member 15 are of sufficient thickness to give an adequate bearing surface for the wrist pin 8, as illustrated in Figure 2.

A clamp block 18 is fitted in a transverse groove 19 in the bearing member 15, and the block 18 and bearing member 15 have aligned key ways 20 and 21 provided to receive the

wedge shaped key 22 which is fitted through aligned keyways 23 and 24 in the flanges of the bar 9. A cap screw 25 is fitted through a suitable opening in the end flange 26 of the bearing member 15 and is threaded through the clamp block 18. By tightening up on this cap screw the block 18 is clamped against the key 22 and the key held against detachment and forms an abutment for the bearing member 15 and said bearing is thus securely held in place. As the wrist pin bearing becomes worn the key 22 may be driven further in and the wear thus taken up.

As before stated it often becomes necessary to detach the pitman from the wrist pin. In order to accomplish this the set screw 25 is loosened and the key 22 removed. The bearing member 15 may then be easily lifted out of place, a hand grip 27 being formed on it for this purpose. The pitman may then be readily lifted off of the wrist pin by means of the hand grip 14, said wrist pin passing out through the slot 11.

In order to lubricate the bearing an oil reservoir 28 is provided in the bearing member 15 and when filled with oil the lubricant will reach the bearing through the port 29 in the upper half of the bearing, as illustrated in Figure 8.

30. What we claim is:—

1. A pitman formed with two bearing members, which, when assembled, form a bearing, a removable key passing through a key way in said members and securing them together, a clamp block formed with a keyway through which the key passes and means for locking said block in frictional engagement with the key.

40. 2. A pitman bearing formed with two bearing members, one of which has a side slot at substantially a right angle to the bearing axis, one side of the slot forming a transverse shoulder, a removable abutment disposed transversely with respect to said axis, and the other of which fits between said shoulder and abutment and interlocks with the latter and closes said slot when the members are in assembled position.

50. 3. A pitman having a wrist pin bearing formed with two bearing members, one of which is formed with a fixed transverse end shoulder, a movable abutment carried by said member and disposed transversely of said bearing, said pitman having a side slot between said shoulder and abutment, the other bearing member fitting into said slot and between said shoulder and abutment when the members are assembled together, said slot being adapted to permit the lateral movement of the wrist pin into or out of the bearing.

60. 4. A pitman formed with two members, one formed with a transverse end shoulder having a wrist pin bearing, a removable

abutment arranged substantially parallel with the shoulder and carried by said member, the said member of said pitman having a side slot between said shoulder and abutment, the other member being fitted 70 into said slot between said shoulder and abutment and being secured in position by said abutment, and having an end plate abutting the member first named, said side slot being cut through the side of the pitman to permit the movement of the wrist pin therethrough, a line at right angles to the axis of the bearing.

5. A pitman having a transverse shoulder at its outer end forming a fixed bearing 80 member, a removable abutment carried by the pitman and arranged substantially parallel with, and spaced from said shoulder, said pitman having a side slot between said bearing member and abutment, a removable 85 bearing member fitted between said shoulder and abutment and held in place by said abutment, an end plate carried by said removable member and abutting the fixed member, said bearing members, when assembled, forming a complete bearing, said slot being disposed to permit the movement of the removable bearing into place on a line parallel with the bearing axis.

6. A pitman having a transverse shoulder, 95 forming a fixed bearing member at its outer end, a removable key carried by the pitman and arranged substantially parallel with and spaced from the shoulder, a removable bearing member fitted between said 100 shoulder and key and held in position by said key and formed with an end plate which abuts the fixed member, said bearing members, when assembled, forming a complete bearing, said shoulder and key being disposed to permit the insertion or removal 105 of the removable bearing member on a line parallel with the bearing axis.

7. A pitman having a transverse shoulder, forming a fixed bearing member at its outer 110 end, a removable key carried by the pitman and arranged transversely with respect to, and spaced from the shoulder, said pitman having a side slot between the shoulder and key, a removable bearing member fitted 115 between said shoulder and key and movable into and out of position on a line parallel with respect to the bearing axis and being held in position by said key, said bearing members, when assembled forming a complete bearing and means for securing said key in the pitman.

8. A pitman bearing formed of a bearing member which has a side slot at substantially right angles to the bearing axis forming a transverse shoulder provided with a half bearing, a removable abutment carried by said member, a plate which is adapted to fit against the side of said member, a lateral projection carried by the inner 125 130

face of said plate which projects through said slot and rests against said abutment and is formed with a half bearing, said half bearing, when so assembled, forming 5 a complete bearing.

9. A pitman bearing formed with two bearing members, one of which has a side slot forming an end shoulder which has a half bearing, the other member including 10 an end plate adapted to fit against the first mentioned member and a projection formed integrally with said plate and adapted to fit through said slot and formed with a

half bearing, said half bearings, when assembled, forming a complete bearing and a 15 removable key extending through said first mentioned member and disposed transversely with respect to said bearing axis and between which and said shoulder said projection is disposed, said key forming means 20 for securing said members in assembled relation.

In testimony whereof we have signed our names to this specification.

ALEXANDER THOMSON.
